TRACTION RAIL ANCHORS

Nelson K. Moses, Ashtabula, Ohio, assignor to Railroad Rubber Products, Inc., a corporation of Florida
Filed Aug. 29, 1952, Ser. No. 307,078
4 Claims. (Cl. 238—283)

This invention relates to improvements in rail-tie units having a rubber pad between the tie and the tie plate as well as between the tie plate and rail, and to rail-tie units consisting solely of a single rubber pad.

Field of invention

It has for many years been standard practice to support rails by mounting them upon steel tie plates placed upon wooden cross ties and spiking the rail and tie plates to one another and to the cross tie. The rail-tie units so constructed have been subject to many difficulties and inadequacies, foremost among which has been the inability of the rail-tie unit to withstand, distribute and cushion impact loads. Consequently, abrasion of the component parts of the rail-tie unit has been common, leading to severe and destructive wear, non-uniformity of gauge and track level, fracture of the rails, tie plates and cross ties, and opening of the units permitting ingress of corrosive materials between the component parts to yield corrosion and permit electrolysis to occur. The passage of rolling stock over the rails has resulted in longitudinal creeping of the rails over the tie plates, and the supporting tie plates have been moved in a direction transverse to the rails along the cross ties, resulting in change and non-uniformity of the gauge of the track. As a result, track maintenance has been unduly expensive.

Objects

It is an object of the present invention to distribute and cushion impact loads incident to the passage of rolling stock over the rails by positioning a rubber rail abrasion pad as described herein between the base flange of the rail and the top surface of the steel tie plate upon which the rail is mounted, and by positioning a rubber tie pad as described herein between the tie plate and the cross tie.

It is a further object of the invention to provide a rubber tie pad having surface irregularities on both the upper and lower surfaces thereof which will anchor the pad to the under surface of the tie plate and to the upper surface of the cross tie to prevent motion of the tie plate along the length of the cross tie.

It is also an object of the invention to provide a rubber tie pad which will extend tie life, absorb shock, impact and vibration, transmit track loads over a greater tie area, seal out abrasive grit and water, reduce tie abrasion and splitting, stabilize subgrade firmness, stop spike loosening, reduce frictional wear, reduce winter maintenance and shimming, and generally permit travel over the rails with greater safety and comfort at higher speeds, together with lower track maintenance costs.

It is also an object of the invention to provide a rail abrasion pad having surface irregularities on both the upper and lower surfaces thereof to anchor the pad against the under surface of the base flange of the rail and against the upper surface of the tie plate to thereby prevent longitudinal creeping of the rail with respect to the tie plate.

It is also an object of the invention to provide a rail abrasion pad which will function to cushion out impacts, vibrations and shocks at their point of origin (the base of the rail), as well as to reduce corrosion, electrolysis, abrasion and fracture of rails, and to generally permit rail travel with greater safety and comfort at higher speeds and with lower track maintenance costs.

2

It is also an object of the invention to provide an anchor seal rail abrasion pad of substantially uniform cross-section having surface irregularities on both the upper and lower surfaces thereof. The surface irregularities on the upper surface of such a pad may be used to bear against the under surface of the base of the rail to anchor the pad to the rail and prevent longitudinal creeping of the rail, and the surface irregularities on the lower surface of the pad may be used to bear against the cross tie to anchor the pad to the cross tie to thereby prevent motion of the pad along the length of the cross tie.

Still further objects and the entire scope of applicability of the present invention will become apparent from the detailed description given hereinafter; it should be understood, however, that the detailed description, while indicating preferred embodiments of the invention, is given by way of illustration only, since various changes and modifications within the spirit and scope of the invention will become apparent to those skilled in the art from this detailed description.

General description

The objects of the invention are realized by providing an anchor seal tie pad made of natural rubber and possessing irregularities as described on both its upper and lower surfaces, between the cross tie and the tie plate, by providing a rail abrasion pad made of natural rubber and possessing irregularities as described on both its upper and lower surfaces between the lower surface of the base of the rail and the top surface of the tie plate. Such a pad made of natural rubber and possessing such irregularities on both its upper and lower surfaces may also be used between the lower surface of the base of the rail and the top surface of the cross tie.

The discussion which follows will best be understood with reference to the accompanying drawing wherein:

FIGURE 1 is a picture view of the assembled rail-tie unit of the present invention;

FIGURE 2 is a cross-sectional view through the assembled rail-tie unit shown in FIGURE 1 taken along line 2—2 of FIGURE 1;

FIGURE 3 is an exploded picture view showing the component parts of the rail-tie unit of the invention;

FIGURE 4 is a picture view on an enlarged scale of the rail abrasion pad of the invention;

FIGURE 5 is a picture view on an enlarged scale of the anchor seal tie pad of the invention; and

FIGURE 6 is an exploded picture view of another embodiment of the invention in which no tie plate is employed.

Referring to the drawing, and to FIGURES 1, 2 and 3 in particular, 10 is an ordinary wood railroad cross tie set in ballast 11. Traction rail 12, of standard construction, is shown mounted upon tie plate 13 by means of spikes 14. A rail abrasion pad 20 is positioned upon the top surface of the tie plate 13 between upstanding shoulders 18 of the tie plate and beneath the lower surface of the base flange of the rail 12. The tie plate 13 is mounted upon cross tie 10 and anchor seal tie pad 30 is positioned between the lower surface of tie plate 13 and the top of the cross tie 10. The tie plate 13 is fastened to the cross tie 10 by means of spikes 15.

The rail-tie unit has been shown with spikes employed in each of the spike-receiving apertures as in the tie plate. However, it should be understood that only a minimum number of spikes are employed in the original installation of the rail-tie unit in accordance with conventional practice in the industry.

As can be seen from FIGURE 2, spikes 14 which fasten the rail 12 to the tie plate 13 pass through apertures 16 in the tie plate 13 adjacent the rail abrasion pad 20, through the anchor seal tie pad 30 and then into the cross tie 10, the rail 12 being held down by contact

with the under surface 14a of the head of the spikes 14. Spikes 15 pass through apertures 17 in the tie plate 13, through the anchor seal tie pad 30, and then into the cross tie 10. Tie plate 13 is held down by the under surface 15a of the spikes 15.

The action of the train in passing over the track causes the wheels of the train to press downwardly, longitudinally and outwardly upon the rails, and tends to urge the rails to move in a direction longitudinal to their length and outwardly in a direction transverse to their length. As a result of this downward, longitudinal and sidewise pressure against the rails, there is a tendency for the rails to creep and spread and to force the tie to sink unevenly into the supporting ballast 11.

With reference to FIGURES 3 and 4 of the drawing, it can be seen that the upper and lower surfaces of the rail abrasion pad 20 possess irregular surfaces generally designated as 21 and 21', respectively. These surfaces in the form shown contain ridges 22 and 22', respectively, and depressions 23 and 23', respectively, having a grain which runs generally transverse to the longitudinal direction of the rail. The rail abrasion pad 20 is formed with thick side shoulders 25, having inner surfaces 26. The distance between the inner surfaces 26 of the side shoulders 25 is the same as the width of the tie plate 13, so that these inner surfaces will bear against the side edges of the tie plate 13, and lock the pad against longitudinal movement on the tie plate.

With reference to FIGURES 3 and 5, the anchor seal tie pad 30 is positioned between the upper surface of the tie 10 and the lower surface of the tie plate 13. The upper and lower surfaces, 31 and 32, respectively, of the anchor seal tie pad 30, are irregular and in the form shown contain ridges 33 and 33', respectively, and depressions 34 and 34', respectively, shown in this embodiment as being grained to run in a direction generally parallel to the longitudinal direction of the rail.

The action of the rail abrasion pad 20 and the anchor seal tie pad 30 to resist the creeping and sidewise motion of the rail due to the forces placed upon it by the motion of rolling stock upon the rail, is generally as follows.

The under surface of the base flange of the rail bears directly against the ridges on the upper surface of the rail abrasion pad 20 and the top surface of the tie plate bears against the ridges of the lower surface of the pad. The forward motion of the rails is substantially eliminated by the action of these ridges, which run in a direction transverse to the length of the rail. The sidewise pressure of the rail has a tendency to force the rail abrasion pad toward the outside of the tie plate 13, and this action is resisted by the upstanding shoulders of the tie plate. The forward motion which is transmitted from the rail to the tie plate 13 is resisted by the spikes 15, the surface configuration of the tie pad 30 assisting in this regard. The spikes 15, especially because of the resilient mounting of the tie plate 13 to the cross tie 10, cannot hold the tie plate 13 with sufficient rigidity to prevent the sidewise displacement of the tie plate 13 with respect to the tie 10, which results from the very great sidewise pressure exerted by the wheels of the train upon the rails. The ridges 33 and depressions 34 on the upper and lower surfaces of the anchor seal tie pad 30 which run in a direction generally parallel with the length of the rail provide the additional resistance to sidewise displacement necessary to substantially limit any tendency of the tie plate 13 from being displaced from its original position with respect to the length of the tie 10.

With reference to FIGURE 6 of the drawing, an alternate embodiment of the invention in which no tie plate is employed is illustrated. It can be seen that the upper and lower surfaces of the anchor seal rail abrasion pad 40 possess irregular surfaces generally designated as 41 and 41', respectively. These surfaces contain ridges 42 and 42', respectively, and depressions 43 and 43', respectively. The grain of the irregular upper surface 41

runs generally transverse to the longitudinal direction of the rail, while the irregular lower surface 41' of the pad has a grain which runs generally parallel to the longitudinal direction of the rail. The under surface of the base of the rail bears against the ridges 42 on the upper surface of the pad. These ridges 42 run transversely to the length of the rail and act to prevent longitudinal creeping of the rail with respect to the pad. The upper surface of the cross tie bears against the ridges 42' on the under surface of the pad. These ridges 42' run generally parallel to the length of the rail and act to prevent transverse displacement of the pad along the cross tie.

The anchor seal rail abrasion pad 40 just described is usually thicker than either the rail abrasion pad 20 or the anchor seal tie pad 30 previously described, the thickness of the pad and its resiliency being designed with a view to conditions under which it is to be used, optimum results being obtained when there is a deflection under normal load of about $\frac{1}{8}$ inch. As shown in FIGURE 6, the upper surface 41 is not necessarily parallel to the lower surface 41' of the pad, but is preferably transversely tilted or canted as shown, to provide a cant to the rail. As shown in FIGURE 6, the thinner side of the pad 40 is pointed toward the inside of the track, and the thicker portion is pointed away from the track to provide a canting of the rails of the track toward one another.

The rail is secured to the anchor seal rail abrasion pad 40 and the pad secured to the cross tie by means of spikes 44, driven through the pad and into the tie. The under surface 45 of the head of the spikes bears against the upper surface of the base of the rail to secure it in conventional manner.

Detailed description

The pads of the present invention are made of the highest grade of pure natural rubber composition, which includes, however, the usual fillers, accelerators, catalysts, etc., which are conventionally employed in the manufacture of such rubber products. The pads of the subject invention must be of such material strength that they will not pull apart, rip out at the spikes or compress unequally in different sections thereof, which would result in canting of the rail outwardly on curves or widening of the gauge of the track. The pads are subjected to continual shock, impact and vibration, as well as wide temperature variation, inclement weather, and corrosive liquids, and it is imperative that the resiliency of the pad does not deteriorate under such abuse. Consequently, the inclusion of substantial proportions of synthetic rubber of various types or reclaimed rubber would be highly detrimental, and the term "natural rubber composition" is intended to include rubber compositions containing as their essential ingredients natural rubber, together with the chemicals normally employed in the manufacture thereof, and to exclude the presence of substantial proportions of either synthetic or reclaimed rubber. In this regard, it is of interest to note that the presence of synthetic rubbers tends to make the pads slippery when wet, which is, of course, highly objectionable.

With particular reference to the rail abrasion pad 20, these pads may vary in thickness from a minimum of $\frac{1}{8}$ inch, and normally would have a maximum thickness of about $\frac{3}{16}$ inch. The rail abrasion pad 20 possesses strong and thick rubber shoulders, and these shoulders engage the edges of the steel tie plate and secure the pad in permanent position with respect thereto. Suitable dimensions for these shoulders are $\frac{3}{8}$ inch by $\frac{3}{16}$ inch. The width of the pad is designed to fit snugly between the upstanding shoulders of the steel tie plate.

The upper and lower surfaces of the rail abrasion pad 20 are formed irregularly with alternate ridges and depressions. The shape of the ridges and depressions, the depth of the depressions, the number of ridges per inch of surface, the spacing of the ridges, and the direction of the ridges are all variable.

The surface irregularities are generally formed in a regular pattern, the ridges and depressions thereof being of sufficient size to be easily visible to the eye. The surfaces of the pad 20 positioned between the rail and the tie plate possess ridges which have a direction perpendicular to ridges on the surfaces of the pad 30 positioned between the tie plate and the cross tie.

In regard to the shape of the ridges and depressions, it is not essential that they have any particular configuration, and the depressions and ridges may be square or rounded and not too well defined, i.e., the ridge line need not be smooth, and may, in fact, be undulated, which undulations may provide a secondary series of alternate ridges and depressions at right angles to the first mentioned series, and small pits or craters may exist in the depressions.

In regard to the depth of the depressions, the depth is dependent upon the thickness of the ridges, and may vary from $\frac{1}{8}$ to $1\frac{1}{2}$ times the ridge thickness, although the preferred range is from $\frac{1}{4}$ to 1 times the ridge thickness.

The spaces between the ridges may also vary, a lower limit of $\frac{1}{8}$ the thickness of the ridge being a minimum, and $1\frac{1}{2}$ times the thickness of the ridge being a permissible maximum, although it is preferred to employ a spacing of about $\frac{1}{4}$ to 1 times the thickness of the ridge.

As has been previously stated, the direction of the ridges on the rail abrasion pad 20 is generally transverse to the length of the rail. This does not mean that the direction of the ridges is necessarily perpendicular to the length of the rail, although it might well be so. The direction of the ridges may frequently run as much as approximately 30° off the perpendicular and still be usable.

In regard to the number of ridges per inch of pad surface, variation between 15 and 60 ridges per inch is permissible, although it is generally preferable to have between 20 and 45 ridges per inch.

With reference to the anchor seal tie pad 30, the thickness may range from a minimum of approximately $\frac{1}{8}$ inch to a maximum of approximately $\frac{3}{8}$ inch, the surface configuration of the anchor seal tie pad 30 being the same as that for the rail abrasion pad 20; however, the direction of the ridges is generally parallel to the length of the rail, although the same variation in shape, depth, number, spacing and direction of the ridges and depressions is permissible.

With reference to the surface configuration on the anchor seal rail abrasion pad 40, it should be noted that the direction of the ridges on the upper and lower surfaces thereof will be approximately 90° out of phase. For example, if the surface configuration on the upper surface of the pad 40 is perpendicular to the longitudinal direction of the rail, then there should be ridges on the lower surface of the pad 40 which are parallel to the length of the rail. The direction of the ridges on the upper surface of the pad is preferably perpendicular to the length of the rail. However, great variation in this regard is permissible, and so long as the direction of the ridges on the upper and lower surfaces of the pad is approximately 90° out of phase, the direction of the ridges on the upper surface of the pad may be off the perpendicular by as much as 45° . In all other respects, however, the surface configuration of the anchor seal rail abrasion pad 40 is the same as the surface configuration on both the rail abrasion pad 20 and the anchor seal tie pad 30.

In further regard to the surface configuration of the pads of the present invention, it should be noted that mere roughening of the surface to increase the coefficient of friction of the material will not serve to substantially reduce the tendency of the rail to creep or the tendency of the tie plate toward sidewise displacement. While

such a roughening conceivably might have some beneficial effect, such effect would not be sufficient to prevent motion, and consequently, would be without great utility. On the other hand, the utilization of large corrugations or tread, such as may be found on the tread of conventional automobile tires, is likewise unavailing, since when such large corrugations are resorted to, the ability of the rubber pad to resist great compressive forces is greatly impaired, and there is a tendency for these ridges to bend, rather than merely compress.

When producing the irregular surface of the present invention, the rubber may be molded between dies of suitable configuration to produce the desired ridge structure. For example, the dies of the mold may be scored to form 36 parallel depressions to the inch, each depression being $\frac{1}{64}$ inch wide and $\frac{1}{64}$ inch deep.

The irregular surface of the present invention may be produced in other manners as well. For example, a woven fabric may be employed to provide a suitable configuration as by rolling the rubber in sheet form tightly upon a reel together with an intermediate layer of separating fabric. The wound reels are then placed in an oven or some other suitable vulcanizing chamber, and the rubber vulcanized to produce on both surfaces of the sheet of rubber a complementary image of the surface of the separating fabric. When this technique is employed, the crossing points of the threads in the fabric produce a multitude of closely spaced pits or craters, as well as a series of alternate depressions and ridges. There may be from 200 to 1,000 of such pits or craters per square inch with the individual pits or craters being approximately $\frac{1}{64}$ inch in depth.

The following are illustrative examples of fabrics which may be operatively employed:

	Weight of fabric (ounces):	Weave of fabric
(1)	8.9	38 x 38
(2)	9.25	30 x 30
(3)	11.65	32 x 28
(4)	14.0	23 x 23
(5)	17.25	23 x 23

With respect to the anchor seal tie pad, it will be noted that both the spikes which secure the base flange of the rail to the tie plate, as well as the spikes which secure the tie plate to the tie base, pass through this pad. Ordinary railroad spikes will pass through the thinner sheets of rubber, i.e., those sheets thinner than $\frac{1}{4}$ inch, and consequently, there is no necessity for prepunching holes in the thinner sheets of rubber. On the other hand, when employing anchor seal tie pads 30 of approximately $\frac{3}{8}$ inch in thickness, it is necessary that holes be prepunched in the rubber for the passage of the railroad spikes therethrough. The prepunched holes are made smaller than the diameter of the spike which is to be employed, so that the rubber in the pad surrounding the spike will press against the spike and function to seal the structure against the ingress of liquids.

It is also necessary for spikes to pass through the anchor seal rail abrasion pad 40, and since this pad is usually thicker than $\frac{1}{4}$ inch, it is necessary to prepunch these pads in the same manner as the thicker anchor seal tie pads.

In regard to the thickness of the pads, the thicker pads are intended for use on ties supported by solid or rigid structures, such as bridges, tunnels, trestles or concrete slabs, where the unyielding nature of the underlying supporting structure requires additional resiliency.

Summary

The invention as described above provides new railtie units in which rubber elements cushion shock, distribute loads, prevent destructive abrasion, and seal out injurious liquids to avoid corrosion and electrolysis. In addition, the natural rubber pads of the invention con-

stitute new articles of manufacture. The provision of the irregular surfaces of the invention in the manner described leads to the attainment of rail-tie units which can be easily and quickly installed and which will resist the tendency of the rail to creep and to move transversely.

I claim:

1. In combination, a traction rail, a tie, a tie plate positioned between said traction rail and said tie and having a longitudinal recess of width to receive the base of said traction rail, said recess having an upwardly facing planar bottom portion, a pad made of a resilient material comprised of substantially pure natural rubber as the resilient ingredient mounted within the recess of said tie plate on its planar bottom portion between the recess and the base of said traction rail, said pad having a thickness from about $\frac{1}{8}$ inch to $\frac{3}{16}$ inch and including preformed alternate closely spaced ridges and depressions on its upper rail contacting surface and its lower tie plate contacting surface, the ridges and depressions extending in a direction generally transverse of the rail axis but never deviating from a perpendicular of the rail axis when in assembled relation more than 30° , there being between 15 and 60 ridges per inch of surface, the depth of the depressions being between $\frac{1}{8}$ and $1\frac{1}{2}$ times the thickness of the ridges, said ridges being spaced apart a distance of from $\frac{1}{8}$ to $1\frac{1}{2}$ times the thickness of the ridges, said pad having its longitudinal end portions extending outwardly from transverse edges of said tie plate, and thick shoulders extending transversely of said pad and integrally connected to the outwardly extending end portions of said pad, said shoulders depending downwardly from the end portions of said pad in juxtaposition with the transverse edges of the tie plate to thereby secure said pad to the tie plate and prevent the pad from being worked out longitudinally from its position between the tie plate and the base of said traction rail.

2. In combination, a traction rail, a tie plate having a longitudinal recess of width to receive the base of said traction rail, a tie, a pad made of a resilient material comprised of substantially pure natural rubber as the resilient ingredient positioned on said tie beneath said tie plate, said pad having a thickness from about $\frac{1}{8}$ inch to $\frac{3}{8}$ inch and including preformed alternate closely spaced ridges and depressions on its tie engaging surface and its tie plate engaging surface the ones on opposite surfaces being approximately parallel with each other and deviating from parallel to the rail axis by no more than approximately 30° , there being between 15 and 60 ridges per inch of surface, the depth of the depressions being between $\frac{1}{8}$ and $1\frac{1}{2}$ times the thickness of the ridges, said ridges being spaced apart a distance of from $\frac{1}{8}$ to $1\frac{1}{2}$ times the thickness of the ridges and means to anchor said tie plate to said tie, said last mentioned means including spikes extending through said tie plate and said pad into said tie.

3. In combination, a cross tie, a traction rail having a base flange, a pad made of a resilient material comprised of substantially pure natural rubber as the resilient ingredient placed between the upper surface of the tie and the lower surface of the base flange of said rail, said pad having a thickness from about $\frac{1}{8}$ inch to $\frac{3}{8}$ inch and having preformed alternate closely spaced ridges and depressions on its flange engaging surface and tie engaging surface, the ones on its flange engaging surface extending in a direction approximately perpendicular to the rail axis and deviating therefrom by no more than approximately 45° while the ones on its tie engaging surface extend in a direction approximately 90° out-of-phase with those on the flange engaging surface, there being between 15 and 60 ridges per inch of surface, the depth of the depressions being between $\frac{1}{8}$ and $1\frac{1}{2}$ times the thickness of the ridges, said ridges being spaced apart a distance of from $\frac{1}{8}$ to $1\frac{1}{2}$ times the thickness of the ridges, means to anchor said rail to said tie and including spikes driven through said pad into said tie with the spike heads engaging the flanged base of said rail.

4. In combination, a traction rail; a tie plate having a longitudinal recess of width to receive the base of said traction rail with an upwardly facing planar bottom portion; a tie; a pad made of resilient material comprised of substantially pure natural rubber as the resilient ingredient mounted within the recess of said tie plate on the planar upwardly facing bottom portion between the recess and the base of said traction rail, said pad having a thickness from about $\frac{1}{8}$ inch to $\frac{3}{16}$ inch and including preformed alternate closely spaced ridges and depressions on its upper rail contacting surface and its lower tie plate contacting surface, said ridges and depressions on opposite surfaces being approximately parallel with each other and extending in a direction generally transverse to the rail axis and never deviating from said direction when in assembled relation more than 30° , there being between 15 and 60 ridges per inch of surface, the depth of said depressions being between $\frac{1}{8}$ and $1\frac{1}{2}$ times the thickness of said ridges, said ridges being spaced apart a distance of from $\frac{1}{8}$ to $1\frac{1}{2}$ times the thickness of said ridges, said pad having its longitudinal end portions extending outwardly from transverse edges of said tie plate, thick shoulders extending transversely of said pad and integrally connected to each of the outwardly extending end portions of said pad, said shoulders depending downwardly from the end portions of said pad in juxtaposition with the transverse edges of said tie plate; a second pad made of resilient material comprised of substantially pure natural rubber as the resilient ingredient mounted on said tie and positioned beneath said tie plate, said second pad having a thickness from about $\frac{1}{8}$ inch to $\frac{3}{8}$ inch and including preformed alternate closely spaced ridges and depressions on its upper tie plate contacting surface and its lower tie contacting surface, the ones on opposite surfaces being approximately parallel with each other and none deviating from parallel to the rail axis by no more than approximately 30° , there being between 15 and 60 of said ridges per inch of surface of said second pad, the depth of said depressions between the ridges of said second pad being between $\frac{1}{8}$ and $1\frac{1}{2}$ times the thickness of said ridges, said ridges being spaced apart a distance of from $\frac{1}{8}$ to $1\frac{1}{2}$ times the thickness of said ridges; and means for securing said tie plate to said tie, said last-mentioned means including spikes inserted through said tie plate and said second pad into said tie.
